ABSTRACT: A bag-collecting device for use at the delivery end of a bagmaking machine comprising, in combination, two bag-collecting platens assembled in vertically spaced substantially parallel relationship, each of said platens having a front end and a rear end being coextensive with the other platen at its front end, and means for supporting the platens and reciprocatably moving at least the front ends of said platens between two vertically spaced positions whereby the two platens can be brought into alternative registration with the delivery end of the bagmaking machine, said means for reciprocatably moving the front end of the platens being automatically responsive to a bag counter unit.

PATENT AGENT

BAG STACKER

This invention relates to an apparatus for collecting bags at the delivery end of a bag-making machine.

Bags are produced from plastic sheeting or tubular film on various types of bag-making machines which basically heat-seal the sheeting or film in the form of bags and then cut the bags into individual units. These bags are then delivered to the end of the machine where they are counted, stacked and packaged.

The constantly increasing demand of recent years for plastics bags has induced manufacturers into designing bag-making machines with a much higher output than heretofore. Such a higher output is achieved through higher speeds and through wider machines which form more than one bag at a time from multiple-web streams. While these machines are successful in so far as the output is concerned, they present a certain difficulty at their delivery end where the finished bags must be collected. Various collecting devices have been proposed to automatically count and stack the finished bags, but these devices suffer from the disadvantages that they do not allow one employee to handle more than one web and do not permit the handling of bags of variable sizes.

It is the primary object of this invention to provide a bag-collecting apparatus or bag stacker which is free of the above disadvantages. Additional objects of the invention will appear hereinafter.

Generally speaking, the invention resides in a bag stacker for use at the delivery end of a bag-making machine and comprises a frame and two vertically spaced platens supported by said frame, each platen having a bag-receiving end and a bag delivery end and being actuatable by a pneumatic cylinder in such a way that at least its bag-receiving end is reciprocatably and vertically movable between two predetermined positions, said cylinder being responsive to a timer and bag counter unit.

The specific features and advantages of the apparatus of the invention will become apparent as the following description of the invention progresses, reference being made to the accompanying drawings wherein:

FIG. 1 is a plan view of a specific embodiment of the apparatus of the invention;

FIG. 2 is a front elevation of the same embodiment and

FIG. 3 is a side elevation of still the same embodiment.

The bag stacker illustrated in the drawings is one which is particularly adapted for use in connection with a bag-making machine producing four bags at a time. This specific bag stacker is comprised of a bag-collecting assembly 10 supported on a frame generally indicated at 11.

The bag-collecting assembly 10 consists of two platens 12 and 13 arranged in spaced, generally parallel relationship and held together by means of spacers 14 fixed on their longitudinal sides. Both platens are coextensive at their front ends, that is at the ends which, when the stacker is in use, come into abutment with the delivery end of the bag-making machine. At their rear ends, the platens are staggered with the top platen 13 terminating short of the bottom platen 12 in order to permit easy removal of the bags from said bottom platen.

Each of the platens 12 and 13 is provided at its rear end with a telescopingly slidable extensions 15 which can be drawn outwardly as desired to increase the effective length of the platen for accommodating bags of different lengths. Each slidable extension 15 has at its free end an upstanding flange 16 acting as a stopper for the bags, and a plurality of handholes 17 for easy grabbing of the bags from the platen.

The frame 11 is a rigid structure comprised of two rear legs 18 and 19 and one front leg 20, said rear legs and front leg being held together by means of cross bars 21 and braces 22. The rear legs are located in directly opposite relationship, one on each of the longitudinal sides of the platens adjacent the rear end thereof. Each of said rear legs 18 and 19 is provided at its top with a rigidly secured extension 23 having a pin 24 projecting inwardly of the frame structure. The set of con-

fronting pins so provided constitutes the support for the rear end of the assembly of platens and the portions of the extensions 23 projecting above the pins act as guides for maintaining the platens in proper position. It can be readily appreciated from the above arrangement that the rear end of the platen 12 is only allowed to rest on the pin 24 and that the assembly of platens is thus free to pivot on said pins.

The front leg 20 is located substantially midway between the two longitudinal sides of the platens adjacent the front end thereof and comprises a hydraulic cylinder 25 having its bottom end hinged on the top end of a short post 26. The hydraulic cylinder has a piston rod 27 the free end of which is hingedly connected to the underside of the bottom platen 12 at a point generally located on the prolonged axis of the short post 26.

As shown in FIGS. 2 and 3, the front leg 20 and rear legs 18 and 19 may advantageously be provided with leveling screw 28. The hydraulic cylinder operates through an electrical circuit comprising a bag counter 29, a timer 30, a four way double solenoid valve 31 and a set of switches LS-1, LS-2 and LS-3 actuatable by a cam 32 borne on the piston rod, to raise and lower the assembly of bag-collecting platens at regular intervals and to alternately bring the platens 12 and 13 into registration with the delivery end of the bag-making machine.

As indicated hereinbefore, the bag stacker particularly shown in the drawings is for use with a machine producing four bags at a time. In order to accommodate such a machine, each platen is divided into four individual bag-receiving spaces by metal dividers 33. Each of said four individual spaces is provided longitudinally and centrally thereof, with a bar 34 which affords a better flow of the bags down the platens to the upstanding flanges or end stops 16. Although the dividers 33 and bars 34 could be fixed on the platens in a permanent manner, it has been found most advantageous to have them adjustable. The dividers and bars illustrated in the drawings are thus held on the platens by magnets so that they can be arranged to suit bag-making machines making bags from any number of film webs.

In operation, the bag stacker is placed in such a way that the front end of one of the platens, for example platen 13, is in registration with the delivery end of the bag-making machine. The dividers 33, bars 34 and platen extensions 15 are then adjusted to suit the number of film webs on the bag-making machine as well as the dimensions of the finished bags.

Once bag production has started, the finished bags flow onto platen 13 over the bars 34 and into the individual spaces delimited by the dividers 33 to the end stops 16. As the bags flow and are stacked onto platen 13, they are counted by automatic counter 29. Once a predetermined count has been reached, the second platen 12 is automatically pivoted up into place by means of the cylinder 25. An operator can now remove the bags from the first platen 13, using the handholes 17. The bags are thus in stacks of a definite count and can be packaged in any of the usual methods. While platen 13 is being unloaded, the second platen 12 is stacking bags to the predetermined count and, upon completion, the cylinder pivots platen 13 down into collecting position and platen 12 can now be unloaded.

The automatic operation of cylinder 25 is as follows. When the determined number of bags has been reached on one of the platens, the counter 29 activates the adjustable timer 30 which synchronizes the indexing of the platens with bag delivery. After the set time, the timer 30 energizes one side of the four-way double solenoid valve 31 through limit switch LS-1 which is held closed by the cam 32 on the piston rod 27. The four-way valve shifts, raising the piston rod 27 of the cylinder 25. Halfway through the stroke, limit switch LS-2 is opened momentarily by the cam 32 resetting the timer. At the end of the piston stroke the cam 32 closes limit switch LS-3 placing the opposite solenoid in the circuit. The hydraulic cylinder is now ready for another cycle.

While the invention has been described in connection with a specific embodiment in which the front end only of the bag-collecting platens is reciprocatable between two vertically spaced positions, it should be understood that it is capable of many modifications. Changes, therefore, in the construction and arrangement may be made without departing from the spirit and scope of the invention as disclosed. It is easy to think, for instance, of an arrangement whereby the assembly of platens could be totally reciprocably raised and lowered rather than at its front end only.

What I claim is:

1. A bag-collecting device for use at the delivery end of a bag-making machine comprising, in combination:

A. Two bag-collecting platens, each having a front end and a rear end and being coextensive with the other platen at its front end, and each comprising:

a. at its rear end, a telescopingly slideable extension the free end of which has an upstanding flange acting as as a stopper for the bag,

b. magnetically held and adjustable dividers forming on said platen a member of longitudinal spaces cor-

responding to the number of bags produced at the same time by the bag-making machine, and

c. magnetically held and adjustable bars located centrally and longitudinally of the spaces between said dividers to permit better flow of the bags in said spaces; and

B. Means for supporting said platens and reciprocably moving at least the front ends thereof between two vertically spaced positions whereby the two platens can be brought into alternative registration with the delivery end of the bag-making machine, said means being automatically responsive to a bag counter unit.

2. A device according to claim 1, wherein the means for supporting the platens and reciprocably moving the front end of said platens between two vertically spaced positions

15 consists essentially of a frame comprising means for pivotably supporting the rear end of said platens and a hydraulic cylinder for supporting the front end of said platens, said cylinder being mounted vertically with one end hinged to the underside of the lower platen and the other end hinged to said 20 frame.
